UNITED STATES PATENT OFFICE.

CLARENCE D. PLATT, OF BRIDGEPORT, CONNECTICUT.

ELECTRIC SWITCH.

1,218,890.

Specification of Letters Patent. Patented Mar. 13, 1917.

Application filed April 20, 1916. Serial No. 92,426.

To all whom it may concern:

Be it known that I, CLARENCE D. PLATT, a citizen of the United States of America, residing at Bridgeport, Connecticut, have invented a new and useful Electric Switch, of which the following is a specification.

My present invention has reference particularly to switches of the so-called push button type and has for some of its objects 10 to provide a switch of comparatively light and inexpensive construction, having a quick action and high current carrying capacity.

A special object is to reduce the shock of the switch movements.

15 In the accomplishment of the foregoing and other objects, as will later appear, I employ in combination a swinging contact making lever and a swinging switch operating lever with a spring connection between 20 said levers and interpose in the path of movement of said levers toward each other, a stop or limiting device arranged to determine the final stopping point of the two levers and to cause the movement of one 25 lever to cushion the movement of the other lever. These stops may be and preferably are carried by a bracket in which the two levers are mounted.

Another feature of the invention is the 30 bowing or transverse arching of the operating lever to strengthen the same and a still farther feature is a novel form of connection between the push-buttons and the operating lever.

35 Various other features will appear as the specification proceeds.

In the accompanying drawing I have illustrated the invention embodied in a practical and preferred form but it will be 40 understood that changes and modifications may be made without departing from the true spirit and scope of the invention.

In this drawing:

Figure 1 is a top plan view of the invention embodied in a wall type switch, the cover and supporting yoke being omitted for the sake of clearness.

Fig. 2 is a side view of the switch mechanism detached from the base therefor.

50 Fig. 3 is a longitudinal sectional view of the switch taken substantially on the plane of the line 3-3 of Fig. 1.

Fig. 4 is a drop perspective view of the several parts of the switch mechanism.

55 In the form of the switch herein illustrated the switch parts are all mounted on

a hollow base 7 of insulating material designed to be mounted in a wall or elsewhere by means of a yoke 8 to which the switch base is secured by screws 9.

60

Mounted within the hollow switch base are the relatively stationary switch contacts 10, two only of such contacts being shown.

The main parts of the switch mechanism are supported by a single bracket 11 of 65 arched structure and comprising spaced apart sides 12 connected by a substantially flat top 13, the sides having outstanding attachment lugs 14 at their bases by which the bracket is secured in place, as by means of 70 the screws 15 passed up through the bottom of the base as indicated in Fig. 1.

The bracket 11 supports a swinging contact making lever 16 and a rocking operating lever 17.

75 The contact making lever is illustrated as a substantially U-shaped member having parallel side portions 18 connected at the bottom and provided at their upper ends with outstanding lugs 19 pivotally engaging in sockets 20 provided in the opposite sides of the arched bracket. These pivot lugs are preferably made as shown, as plain straight sided members, free of protuberances or enlargements so that if necessary the sides of 80 the U-shaped contact can be pinched together so that these lugs will pass between the sides of the arched supporting bracket and then spring outwardly through the bearing sockets provided therefor.

90 The rocking operating lever is usually bowed transversely as indicated so as to extend up into the arch of the supporting bracket and is provided with pivot lugs also 95 preferably straight sided as indicated at 21 to engage in the bearing sockets 22 provided in the sides of the bracket.

The switch operating lever has oppositely extending operating arms 23-24 extending 100 to opposite sides of the pivotal center thereof, these arms being usually bent downward from the plane of the highest point of the arch of said lever and substantially flat or bowed slightly upward on top as indicated at 25 in Fig. 4. This transverse bow or arch imparted to the operating arms gives them stiffness and rigidity and prevents them from becoming bent during operation of the switch.

105 A snap action of the parts is secured by connecting a spring 26 between a loop 27 on the lower end of the contact making lever

110

and a loop 28 on the arch of the operating lever, this spring serving, as the operating lever is rocked, to carry the upper end of the spring past the dead center to swing the contact making lever over with a quick snap movement. This movement of the two levers is provided for in the illustration by looping the sides of the contact making lever as indicated at 29 so as to pass around the pivots 21 of the operating lever.

The switch operating lever is actuated in the illustration by two push-buttons 30 and 31. It will be evident from what has been said that when the push-button 30 in Fig. 15 3 is depressed the left hand end of the operating lever will be rocked downward until the upper end of the throwing spring is carried past the pivotal center 19 of the contact making lever whereupon the spring 20 will then act to quickly snap the contact making lever to the left.

The movement of the operating and contact making levers is limited in my present invention by stops interposed in the path of movement of these two levers toward each other, these stops taking the form in the present disclosure of inturned oppositely disposed lugs 32 carried by the sides of the arched bracket at the opposite ends thereof 30 and adapted to be engaged underneath by the sides of the upwardly swinging contact making lever and on top by the lugs 33 outstanding from the opposite edges of the switch operating lever.

35 The switch operating and contact making levers engage the opposite sides of the stop lugs practically simultaneously and so serve in effect the one to cushion the blow of the other. This brings the parts to a quick stop 40 with but slight shock to any of the parts and enables the making of the parts relatively light. Another advantageous feature of this structure is that the stop lugs are located at a sufficient distance from the 45 pivot centers of the two levers to bring the levers to a stop without undue shock to any of the parts.

In the switch illustrated the lugs 33 on the operating lever which engage the stop lugs on the bracket extend downwardly slightly below the plane of the relatively flat top of the operating arms 23—24, this giving the transversely arched configuration referred to.

55 The connection between the operating push-buttons and switch operating lever is of novel construction and is made by providing the shank 34 of each button with a notch 35 in the lower edge thereof opening 60 into a pivot opening 36 and the operating arm with a notch 37 in its lower end separated from a slot 38 in line with said notch by an intervening pivot bar portion 39 which is received in the bearing opening 36.

65 With this construction, to contact the

push-buttons to the operating lever it is merely necessary to slip the notched edge of the push-button shank over the notched edge of the operating arm until the pivot bar 39 engages in the pivot opening 36 as 70 indicated at the left in Fig. 4 and then to turn the push-button upward so that the end portion of the shank 34 fits within the slot 38 as indicated at the left in Fig. 3. Aside from the ease of assemblage this connection has the advantage of bracing the shank of the push-button against lateral movement with respect to the working of the operating lever.

75 From the foregoing it will be apparent 80 that the switch of my invention is quick and powerful in its action and consists of but few parts of simple and inexpensive construction.

What I claim is:

85 1. In a switch of the character described, the combination with a freely swinging contact making lever, a freely swinging operating lever and a spring connection between said levers tending to swing the end 90 portions of said levers together, of stop means at one side of the point of support of the levers interposed in the path of movement of said levers toward each other and engaged on opposite sides by said levers 95 to fix the stopping point of both levers whereby the force of impact of one lever against said stop means will be opposed by the force of impact of the other lever and means for actuating the operating lever 100 against said stop means.

2. In a switch of the character described, a supporting base, a switch operating lever pivoted on said base having outstanding operating arms disposed flatwise with the 105 greatest dimension thereof at right angles to the plane of movement of such arms, a pivoted contact making lever, a spring connection between said levers and means connected with the relatively flatwise disposed 110 outstanding arms of the switch operating lever for actuating said lever.

3. In a switch of the character described, the combination with a supporting base, of a switch operating lever pivotally mounted 115 on said base and provided with transversely arched outstanding operating arms, operating means connected with said transversely arched outstanding arms, a pivoted contact making lever and a spring connection between the levers.

4. In a switch of the character described, a base, a switch operating lever pivotally supported on said base and provided with outstanding operating arms disposed flatwise with the greatest dimension thereof at right angles to the plane of movement of such arms, push buttons connected with the end portions of said relatively flat outstanding arms, stops disposed in the path of 120 125 130

movement of said arms substantially in line with the points of connection with the push buttons therewith whereby to take the strain of pressure on said push buttons and a contact making device connected with the operating lever.

5. In a switch of the character described, a supporting base, a switch operating lever pivotally mounted on said base and provided with operating arms disposed flatwise with the greatest dimension thereof at right angles to the plane of movement of such arms having outstanding stop lugs at the ends thereof, push buttons connected with the relatively flat operating arms substantially in line with said outstanding stop lugs, stops disposed in the path of movement of said stop lugs on the operating arms and a contact making device connected with the switch operating lever.

6. In a switch of the character described, a supporting base, a freely swinging operating lever pivotally mounted on said base

and provided with outstanding operating arms, push buttons connected with the end portions of said operating arms, stops disposed in the path of movement of the operating arms of the freely swinging operating lever and substantially in line with the points of connection of the push buttons therewith to thereby take the strain of pressure on the push buttons and a contact making device connected with the operating lever.

7. In a push-button switch, the combination of an operating lever having a notch in the edge thereof and a slot therein substantially in line with the notch in the edge but separated therefrom by an intervening bar and a push-button having a shank provided with a pivot opening therein for the intervening bar aforesaid and a notch extending from the edge of the shank into said pivot opening.

CLARENCE D. PLATT.

It is hereby certified that in Letters Patent No. 1,218,890, granted March 13, 1917, upon the application of Clarence D. Platt, of Bridgeport, Connecticut, for an improvement in "Electric Switches," errors appear in the printed specification requiring correction as follows: Page 2, line 99, claim 1, after the word "lever" insert the words *against said stop means*; same page and claim, strike out line 101; and that the said Letters Patent should be read with these corrections therein that the same may conform to the record of the case in the Patent Office

Signed and sealed this 3d day of April, A. D., 1917.

[SEAL.]
